George C. Bright, Tucson, Ariz.

Application April 29, 1948, Serial No. 146,026

Term of patent 7 years

(Cl. D74—1)

To all whom it may concern:

Be it known that I, George C. Bright, a citizen of the United States, residing at Tucson, county of Pima and State of Arizona, have invented a new, original, and ornamental Design for a Map Holder or Similar Article, of which the following is a specification, reference being had to the accompanying drawing, forming a part thereof.

Fig. 1 is a plan view of a map holder or similar article, showing the essential features of my new design in full lines, the broken lines being for illustrative purposes only.

Fig. 2 is a side elevation of the same; and

Fig. 3 is a sectional view as taken on line 3—3 of Fig. 1.

The dominant features of my design for a map holder or similar article, reside in the specific configuration of the same as noted by the concavity at the center, as seen most clearly in Fig. 3,

in combination with the outwardly flaring convolutions at each end of the holder, as seen most clearly in Figs. 1 and 3.

I claim:

The ornamental design for a map holder or similar article, substantially as shown and described.

GEORGE C. BRIGHT.
